STONE CUTTER GAUGE

William B. Owens, Santa Monica, Calif., assignor
of one-half to John C. Steele, Santa Monica,
Calif.

Application August 21, 1933, Serial No. 686,044

5 Claims. (Cl. 33—80)

My invention relates to a stone cutter gauge.

It is an object of this invention to provide a gauge for chipping edges on blocks of stone, such as used for monuments, which can be 5 quickly applied and instantly removed by a manually operated handle. Means are also provided on the gauge whereby letters may be ruled or spaced on the stone by a sliding adjustment of a ruler mounted on the gauge, thus eliminating 10 the old way of having to measure the stone and space the letters evenly from each side.

In particular, the invention consists of a flat metal bar having clamping means for engaging the block of stone at opposite sides, said clamping 15 means comprising a freely slideable jaw at one end of the bar and a spring pressed jaw at the other end, the latter being instantly releasable by means of a manually operated handle whereby the bar is released from the stone.

20 With the above and other objects in view, which will appear as the description proceeds, my invention consists in the construction and arrangement of parts hereinafter described and claimed.

25 In the accompanying drawing, which forms a part of the specification, I have illustrated a preferred embodiment of my invention and in which:

Fig. 1 is a top plan view showing my gauge 30 clamped to a block of stone.

Fig. 2 is a vertical section along line 2—2 of Fig. 1.

Figs. 3 and 4 are sections taken on the lines 35 3—3, and 4—4, respectively, on Fig. 2.

35 Figs. 5 and 6 are enlarged detail views of the jaws shown in Fig. 2.

Fig. 7 is a modification and a similar view 40 of the jaw shown in Fig. 5.

Referring to the drawing, the gauge consists 45 of a flat metal bar 10 provided with a spring pressed jaw indicated as a unit at 11 and a jaw bodily slideable on the bar 10 indicated as a unit at 12. The spring pressed jaw 11 consists of a pressure member 13 extending substantially 50 at right angles to the bar 10 and provided with a horizontal slot 13' through which the bar 10 passes. The lower end of the pressure member 13 is, preferably, provided with a plug 14 which 55 directly engages the block of stone S. This plug 14 is, preferably, made of lead, rubber or like material which will not mar the face of the stone.

The outer end of the bar 10 is bent vertically 55 downward to provide a seat 15 between which

and the pressure member 13 a helical spring 16 is disposed.

The pressure member 13 is screw tapped for the reception of a screw threaded bolt 17 passing through the seat 15 and having its outer end screw threaded for the reception of a wing nut 18. The spring 16 tends to push the pressure member 13 away from the seat 15 against the stones S and its tension may be adjusted by the operation of the nut 18. The upper part 10 of the pressure member 13 is provided with a handle or finger 19 preferably curved slightly inwardly.

The freely slideable jaw 12 at the other end 15 of the bar 10 comprises a bracket 20 having downwardly extending ears 21 connected by a horizontal cross member 22, which is slidably mounted on the bar 10.

A pressure member 23 is pivoted on a pin 24 mounted between the ears 21—21. The lower 20 part of the pressure member 23 is provided with a plug 25 of lead or rubber directly engages the block of stone S. The pressure member 23 is provided at its upper end with a cam 26 which engages and presses the bar 10 against the cross 25 member 22 of the bracket 20, thereby securely clamping the jaw 12 in position in relation to the bar 10. As clearly shown in Fig. 6, the cam 26 limits the swinging movement of the pressure member 23 just short of the vertical position of the latter.

In Fig. 7, a modified form of jaw 11 is illustrated. Here the helical spring 16 is mounted on top of the bar 10 and fastened thereto at one end with a rivet 27, the other end of the 35 spring 16 being attached to the handle 19 of the pressure member 13.

The letter spacing rule used in conjunction 40 with the gauge consists of a flat bar 28 which is mounted on top of the bar 10. It passes between the cross member 22 of the bracket 20 and the bar 10, there being a recess 29 provided between one half of the cross member 22 and the bar 10, the cross member 22 being slightly offset, as shown in Fig. 4. Between the 45 bar 28 and the bar 10 is a strip of tracing cloth or the like 30, which projects from the bar 28 outwardly to the edge of the bar 10. Upon this tracing cloth 30 the spaces of the letters or numerals are laid off. The tracing cloth 30 is 50 so positioned prior to its insertion between the bars 28 and 10 that the body of the letters is equally spaced from the sides of the block of stone, whereupon the bar 28 is secured to bar 10 by means of screws 31 which are screw threaded 55

through registering screw threaded perforations in bars 23 and 10. The sheet of tracing cloth does not interfere with the screwing down of screws 31. The letters or the like are now drawn 5 either upon the stone direct to be cut out or, as shown in the drawing, upon a sheet of rubber composition 32 which covers the top of the block of stone and on top of which the gauge rests. The letters are now stencilled out in the 10 composition 32 and are cut into the block with a sand blast to the desired depth.

If the letter spacing rule is to be used without using the jaws 11 and 12 for clamping the same on to the block of stone, in that case the 15 bar 10 is fastened to the sheet 32 by means of set screws 33 to prevent displacement.

Operation

The gauge is placed upon the top of the block 20 of stone and the handle 19 is moved outwardly against the pressure of the spring 16 for a slight distance, and the movable jaw 12 is moved against the side of the stone until the plug 25 touches the same. The handle 19 is now released and the spring 16 will move the movable jaw 12 against the block of stone and at 25 the same time swing the pressure member 23 of the movable jaw 12 slightly on its pivot 24 until the cam 36 limits further swinging movement, clamping the movable jaw 12 firmly in 30 position on the bar 10.

The gauge now being clamped in position, the stone cutter may chip the edge as desired or he may manipulate the letter spacing rule, 35 as above described. To release the gauge it is merely necessary to move the handle 19 away from the stone to release the jaw 11 from engagement therewith. The gauge may now be removed by lifting the handle of the jaw 11, 40 with the bar 10 connected thereto, so as to pivot for an instant on plug 25 of the movable jaw.

Various changes may be made by those skilled 45 in the art in the construction and arrangement of parts without departing from the spirit of my invention as claimed.

I claim:

1. A stone cutter's gauge comprising a bar, 50 a jaw slidably mounted on the bar for engaging one side of a block of stone, and a spring pressed jaw for engaging the opposite side, means operative when the slideable jaw is moved against the side of the block of stone for clamping the slideable jaw on the bar, and means for moving the spring pressed jaw against the pressure of the spring and away from the stone to release the gauge therefrom.

2. A stone cutter's gauge comprising a flat 55 bar, a jaw slidably mounted on the bar for engaging one side of a block of stone, and a spring

pressed jaw for engaging the opposite side, said slideable jaw comprising a bracket slideable on the upper face of the bar, a pressure member pivoted to the bracket and depending therefrom, and means for clamping the bar and bracket together, and manually operated means for moving the spring pressed jaw against the pressure of the spring and away from the stone. 5

3. A stone cutter's gauge comprising a flat 10 bar, a jaw slidably mounted on the bar for engaging one side of a block of stone, and a spring pressed jaw for engaging the opposite side, said slideable jaw comprising a bracket slideable on the upper face of the bar, a pressure member pivoted to the bracket and depending therefrom, 15 and a cam fastened to the pressure member and adapted to clamp the bar and the bracket together, said spring pressed jaw including a second pressure member depending from the bar, a spring tending to move the second pressure member 20 toward the side of the stone, and a handle for moving the second pressure member against the tension of the spring and away from the stone.

4. A stone cutter's gauge comprising a flat 25 bar, a jaw slidably mounted on the bar for engaging one side of a block of stone, a spring pressed jaw for engaging the opposite side, said spring pressed jaw including a pressure member depending from the bar, and a handle 30 connected to the pressure member and extending above the bar, said handle and pressure member being mounted for limited slideable movement along the bar, and means limiting the movement of the pressure member toward the side 35 of the stone.

5. A stone cutter's gauge comprising a flat 40 bar, a jaw slidably mounted on the bar for engaging one side of a block of stone, and a spring pressed jaw for engaging the opposite side, said 45 slideable jaw including a bracket slideable on the upper face of the bar, a pressure member pivoted to the bracket and depending therefrom, said pressure member having a cam adapted to engage the under side of the bar for clamping the bar and the bracket together, said spring pressed jaw including a second pressure member depending from the bar and a handle integral therewith extending above the bar and provided with a slot through which the bar passes, 50 the adjacent end of the bar being turned downwardly to form a spring seat, a coiled spring mounted between the spring seat and the second pressure member, a bolt passing through the spring seat and secured to the second pressure 55 member, and a nut on the bolt for adjusting the tension of the spring.

WILLIAM B. OWENS.
